(57) **CLAIM**

The ornamental design for a nasal dilator with relief cuts, as shown and described.

DESCRIPTION

FIG. 1 is a top plan view of a first embodiment of a nasal dilator with relief cuts;

FIG. 2 is a perspective view thereof, shown in a state of use;

FIG. 3 is a flat perspective view thereof;

FIG. 4 is a top plan view of a second embodiment of a nasal dilator with relief cuts;

FIG. 5 is a perspective view thereof, shown in a state of use; and,

FIG. 6 is a flat perspective view thereof.

Long broken lines depicting a nose in the side-view figures are directed to environment. Short broken lines show portions of the nasal dilator with relief cuts that form no part of the claimed design. Heavy dot-dash broken lines show the bounds of the claimed design. Light and irregularly-broken lines show surface contours and shading.
